UNITED STATES PATENT OFFICE.

SIDNEY SMITH, OF DETROIT, MICHIGAN.

ELECTRICAL BINDING-SCREW OR TERMINAL.

1,103,544.

Specification of Letters Patent. Patented July 14, 1914.

Application filed February 16, 1914. Serial No. 818,924.

To all whom it may concern:

Be it known that I, SIDNEY SMITH, citizen of the United States, residing at Detroit, county of Wayne, State of Michigan, have 5 invented a certain new and useful Improvement in Electrical Binding-Screws or Terminals, and declare the following to be a full, clear, and exact description of the same, such as will enable others skilled in the art 10 to which it pertains to make and use the same, reference being had to the accompanying drawings, which form a part of this specification.

My invention relates to an electrical binding screw or terminal, shown in the accompanying drawings and more particularly pointed out in the following specification and claims.

One object of this invention is to provide 15 a device simple and inexpensive in construction and capable of receiving and engaging the several forms of connectors or conductors in common use.

Another object is to provide for the adjustment of the terminal stud so that it may be adapted to receive the conductor at whatever angle or direction it may be most convenient to lead the same to the terminal.

Other advantages and improvements will 20 hereafter appear.

In the drawings accompanying this specification: Figure 1 is a longitudinal section of the terminal with parts broken away and in elevation. Fig. 2 is a like sectional view 25 showing the opposite end of the post indicated in Fig. 1, with a removable cap engaged thereto, this device being employed on certain electrical apparatus in which it is desired to connect the elements lodged with 30 in an inclosing wall to a post with which other conductors are engaged on the outside of the wall. Fig. 3 is a cross sectional view through the cap on line 3-3 of Fig. 1. Fig. 4 is a side elevation of the cap. Fig. 5 35 is a perspective view of a modification of the cap showing it circular in form and milled to facilitate adjustment. Fig. 6 is a longitudinal section through a modification, in which the post and cap portion are integral. 40 Referring now to the letters of reference placed upon the drawings: A denotes a post screw threaded throughout its length having an enlarged head A' which may also be 45 screw threaded.

50 B indicates an annular cap provided with

a central smooth bored aperture b through which the post A projects.

C, denotes a cap nut having a screw threaded engagement with the annular cap B, and is provided with a central aperture o through which a wire or other conductor of suitable form may be led;—the end of the conductor projecting beyond the cap nut bent at right angles to its body portion, that it may be secured between the enlarged end A' of the post A, and the end of the cap nut C, by adjusting the latter. The head of the cap nut C is squared and is also provided with a kerf c' that it may be adjusted either with a wrench, or a screw driver, as found most convenient. The cap B is threaded a portion of its length to receive the cap nut C and the enlarged end A' of the post A,—it being recessed at b' so that when the post and cap are assembled as shown in Fig. 1, the annular cap B is free to turn upon the post A without disturbing the adjustment of the cap with respect to the post. It may thus be turned in either direction in order that any of the several apertures provided for the wires or other conductors, may face the angle best adapted for the reception of the conductors.

D is a lock nut on the post A to secure the terminal to the wall of the electrical apparatus to which it may be attached.

b², b³, and b⁴ are transverse apertures of different diameters in the cap B through which wires or other suitable conductors may enter the cap.

b⁵ is a rectangular aperture in the cap through which an electrical connector having a flat or bifurcated blade may project.

E is an electrical connector having a bifurcated blade E' the tines of which project on either side of the stem of the nut C as shown in Figs. 1 and 2.

F is a conductor having a flattened end projecting into the enlarged opening b⁵ of the cap where it is engaged by the end of the cap nut C. The cap B' shown in Fig. 2 is used on the terminal post of certain apparatus when it is desired to connect elements inclosed by a wall G, with the conductors connected with the post on the outside of said inclosing wall. The post A at this end is not enlarged but is threaded directly into the cap B'.

D' is a nut on the post to secure the parts in position.

In the modification shown in Fig. 6 the cap B is integral with the post A, the cap nut C and other parts being identical with like parts previously described.

- 5 Having indicated the several parts by reference letters, the construction and operation of the device will be readily understood. It will be noted that the device is designed to receive the ends of a great variety 10 of forms of electrical conductors, and that they may be readily connected with the terminal stud when led thereto from any direction and under varying conditions. For example a wire may be connected with the 15 terminal through the central aperture c in the cap nut C and given a right angled bend within the annular cap B, the end of the nut being adjusted so as to engage the bent portion of the wire between the nut and the enlarged end of the post;—or wires or other conductors of circular form in cross section and of different diameters may be led into the cap at b², b³, or b⁴, the end of the conductors being engaged by the nut and the 20 enlarged end of the post A. If the conductor employed has a bifurcated end, the tines of the bifurcated portion may be forced between the end of the nut and the outer face of the cap, the tines straddling the stem of 25 the nut, as indicated in Fig. 1:—or if the end of the conductor is provided with a relatively broad flat undivided end, it may be inserted through the rectangular aperture b⁵ of the cap, and the cap nut C adjusted so 30 that it may be engaged between the end of the nut and the wall of the cap, which is also clearly shown in Fig. 1. If desired the large end of the post may engage the threaded portion of the cap and form an anvil 35 against which the end of the conductors may be forced by the adjustment of the cap nut. If it is desired to adjust the apertures of the cap so that they may radiate in any required direction the cap may be rotated on 40 the post without disturbing the adjustment of the lock nut D, when the enlarged end A' of the post is lodged within the recessed portion b' of the cap as indicated in Fig. 1.
- 45 While the enlarged head of the post may 50 or may not be threaded I prefer the latter construction for the reason that the annular cap cannot then be disengaged from the post without first introducing the threaded head into the threaded portion of the cap, even though the cap nut may have been first removed.

Having thus described my invention, what I claim is:

1. An electrical terminal comprising a 60 post having an enlarged head at one end, an annular cap mounted thereon provided with transverse openings and recessed to re-

ceive the head of the post whereby the cap may be rotated upon the post to change the radial direction of the transverse openings 65 in the cap with respect to the post, and a cap nut provided with a projecting stem having a screw threaded engagement with the annular cap whereby it may be brought into impinging relation with the ends of the electrical conductors lodged in the transverse openings of the cap.

2. An electrical terminal comprising a screw-threaded post having an enlarged screw threaded head at one end, an annular cap with transverse openings to receive electrical conductors and tapped at one end to receive the enlarged screw-threaded head of the post, the opposite end of the cap provided with a smooth bore through which the 70 post projects, said cap having also an intermediate recessed portion between the tapped portion and its smooth bore to receive the head of the post in which it is free to turn, whereby the cap may be rotated upon the 75 post without changing its longitudinal adjustment, a cap nut provided with a projecting stem engaging the tapped portion of the annular cap, and a lock nut engaging the post to secure the post in position.

3. An electrical terminal comprising a screw-threaded post carrying an annular cap at one end, said cap provided with a plurality of transverse openings to receive the ends of electrical conductors and also tapped 95 to receive the stem of a cap nut, the cap nut provided with a head overlapping the end wall of the annular cap and having a screw-threaded stem adapted to engage the ends of the electrical conductors lodged in the transverse openings of the annular cap, the overlapping head of the nut being adapted to engage a conductor lodged between the head of the nut and the wall of the annular cap, and a lock nut tapped to receive the post.

4. An electrical terminal comprising a post carrying an annular cap at one end, said cap provided with a plurality of transverse openings to receive the ends of electrical conductors engaged therewith and also 100 tapped to receive the stem of a cap nut, and the cap nut having a screw threaded projecting stem designed to engage the electrical conductors lodged in the transverse openings of the cap,—said cap nut also provided with a central longitudinal bore to receive an electrical conductor inserted through the axis of said cap nut.

In testimony whereof, I sign this specification in the presence of two witnesses.

SIDNEY SMITH.
